Primary Examiner — Mojtaba Tehrani(74) Attorney, Agent, or Firm — The Compton Law Firm, P.C.; Scott D. Compton(57) CLAIM

The ornamental design for a reticle, as shown and described.

DESCRIPTION

FIG. 1 is a front view of a reticle showing my new design; and,

FIG. 2 is another front view of the reticle.

The broken lines showing of the optical medium in the Figures are for illustrative purposes only and form no part of the claimed design. The broken lines showing the environmental structure in FIG. 2 is for illustrative purposes only and forms no part of the claimed design.
